DESIGN FOR A COMPACT

Karl F. Schick, New York, N. Y.

Application February 8, 1945, Serial No. 117,825

Term of patent 3½ years

(Cl. D86—10)

To all whom it may concern:

Be it known that I, Karl F. Schick, a citizen of Czechoslovakia, residing at New York, in the county and State of New York, have invented a new, original, and ornamental Design for a Compact, of which the following is a specification, reference being had to the accompanying drawing, forming part thereof.

Fig. 1 is a top plan view of a compact embodying my new design;

Fig. 2 is a side view thereof;
Fig. 3 is a rear end view of the compact; and
Fig. 4 is a bottom view thereof.
The transparent cover is lined for contrasting colors.

I claim:
The ornamental design for a compact, as shown and described.

KARL F. SCHICK.
